US00D813722S

(12) **United States Design Patent** (10) **Patent No.:** **US D813,722 S**
(45) **Date of Patent:** **** Mar. 27, 2018**

(54) **ZIPPER PULLER**

(71) Applicant: **ZHEJIANG WEIXING
INDUSTRIAL DEVELOPMENT
CO., LTD.**, Taizhou, Zhejiang (CN)

(72) Inventor: **Yishu Huang**, Zhejiang (CN)

(73) Assignee: **ZHEJIANG WEIXING
INDUSTRIAL DEVELOPMENT
CO., LTD.**, Taizhou, Zhejiang (CN)

(**) Term: **15 Years**

(21) Appl. No.: **29/575,800**

(22) Filed: **Aug. 29, 2016**

(30) **Foreign Application Priority Data**

May 31, 2016 (CN) 2016 3 0214278

(51) **LOC (11) Cl.** **02-07**

(52) **U.S. Cl.**

USPC **D11/221**

(58) **Field of Classification Search**

USPC 24/381-383, 385-387, 414-417,

(57)

CLAIM

The ornamental design for a zipper puller, as shown and described.

DESCRIPTION

FIG. 1 is a front view of a zipper puller according to my design;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

1 Claim, 6 Drawing Sheets
